UNITED STATES PATENT OFFICE.

CHARLES A. CARLSON, OF STILLMAN VALLEY, ILLINOIS.

BARREL-STAND.

1,270,696.

Specification of Letters Patent. Patented June 25, 1918.

Application filed February 2, 1918. Serial No. 215,130.

To all whom it may concern:

Be it known that I, CHARLES A. CARLSON, a citizen of the United States, residing at Stillman Valley, in the county of Ogle and 5 State of Illinois, have invented new and useful Improvements in Barrel-Stands, of which the following is a specification.

This invention comprehends the provision of a barrel stand designed to support a barrel 10 in a manner so that the same can be conveniently tilted and maintained in any desired position, to drain the contents therefrom.

In carrying out my invention use is preferably made of strap iron so shaped as to provide an extremely simple, strong and durable support for the purpose intended, the invention residing in the construction, combination and arrangement of parts as 20 claimed.

In the drawings forming part of the specification, like numerals of reference indicate similar parts of the several views, and wherein:—

25 A perspective view of the stand is shown. A stand constructed in accordance with my invention embodies a pair of spaced vertically disposed members, which are substantially of triangular formation as shown. 30 Each member is identical in construction and is preferably formed from a suitable length of strap iron or like, the intermediate portion 10 constituting the base, and may be of any desired length to provide a proper 35 bearing surface. The base end of each member terminates to provide upwardly extending straight portions 11 which project but a slight distance above the base 10. The straight portions 11 are twisted as at 12 for 40 the purpose of disposing the converging portions 13 edgewise with respect to the base, thus permitting the extremities of the converging portions to be overlapped as shown. In addition to so disposing the converging 45 portions, the twist 12 in the material tends to strengthen the members as a unit. The members are connected together by means of a substantially arch shaped plate 14 which is bifurcated at each end, the separated portions 15 defined by the bifurcations being oppositely curved and riveted or otherwise suitably secured to the base 10 of said members at points adjacent the upturned portions 11 thereof. A substantially U-shaped 50 element 16 is positioned between the said members, and is riveted or otherwise suit-

ably secured to the plate 14 centrally thereof. The parallel limbs 17 of this element are provided with openings disposed in alinement with similar openings formed in 60 the overlapped extremity of the convergingly disposed portions 13 of said members. The parallel portions 17 are connected with said converging portions of said members through the instrumentality of the trunnions 65 18 which project from the barrel supporting annulus 19 passing through the alined openings above mentioned. The trunnions are threaded at their outer ends to accommodate suitable nuts 21 whereby the parts are maintained properly associated, or by means of 70 which the barrel supporting annulus may be held fixed relative to the stand in any given position.

The element 16 is utilized to add strength 75 and durability to the stretcher as an entirety, and is admirably designed and most conveniently disposed for this purpose. The annulus 19 is split as shown, the extremity thereof being offset and disposed in confronting relation as at 22. A headed bolt 23 is passed through the offset extremity and has associated therewith a nut 24. The component parts are associated in a manner to permit the annulus 19 to be spread or enlarged an appreciable degree to facilitate 80 the positioning of a barrel therein or the removal of a barrel therefrom. Subsequent to the positioning of the barrel within the annulus the nut 24 is tightened upon the 90 bolt 23, thus contracting the annulus about the barrel to support the latter in spaced relation to the closed end of the U-shaped element 16. Manifestly, the barrel so supported can be readily and easily tilted to 95 any desired position, as well as maintained in any given position by merely tightening the nuts 21.

While it is believed that from the foregoing description the nature and advantages 100 of the invention will be readily apparent, I desire to have it understood that what is herein shown and described is merely illustrative of the preferred embodiment of the invention, to which I do not limit myself, 105 and that such changes may be resorted to when desired as fall within the scope of what is claimed.

What I claim is:—

A barrel stand comprising a pair of spaced 110 side members, each member being formed from a length of flat material and having a

triangular configuration, a transversely disposed plate connecting said members and secured to the base thereof, the diverging portions of said members being twisted at 5 an appropriate point in their length to lie edgewise in a vertical plane with their extremities overlapped, a substantially U-shaped element arranged with its closed end reposing upon the said plate and secured 10 thereto in any suitable manner, an adjustable annulus disposed between the limbs of the

U-shaped elements, trunnions projecting from said annulus and passed through the limbs of said elements and the overlapped extremities of the side members whereby said annulus is supported for rotation and means 15 associated with said trunnions for holding the parts operatively associated and the annulus in any given position.

In testimony whereof I affix my signature. 20

CHARLES A. CARLSON.
